[57] CLAIM

The ornamental design for a pillow and quilt set, as shown and described.

DESCRIPTION

FIG. 1 is a front view of the pillow and quilt set of the claimed design;

FIG. 2 is a right side view of the quilt of FIG. 1;

FIG. 3 is a rear view of the quilt of FIG. 1;

FIG. 4 is a right side view of the pillow of FIG. 1; and,

FIG. 5 is a rear view of the pillow of FIG. 1.

The left sides of the quilt and pillow are identical to the right side views.
